UNITED STATES PATENT OFFICE.

JOHN S. BODGE, OF LA PORTE, INDIANA.

IMPROVEMENT IN GRAIN-SEPARATORS.

Specification forming part of Letters Patent No. 58,052, dated September 18, 1866.

To all whom it may concern:

Be it known that I, JOHN S. BODGE, of La Porte, in the county of La Porte and State of Indiana, have invented a new and useful Improvement in Mechanisms for Separating Grain and other Substances; and I do hereby declare that the following is a full, clear, and exact description thereof, which will enable those skilled in the art to make and use the same, reference being had to the accompanying drawings, forming part of this specification, in which—

Figure 1 is a plan or top view of my invention, partly in section; and Fig. 2, a side sectional view of the same, taken in the line *x x*, Fig. 1.

Similar letters of reference indicate corresponding parts.

This invention is designed as an improvement on that kind of separators the screens or sieves of which are provided with covers constructed and arranged in such a manner and in such relation with the screens or sieves as to prevent the longer or broader grains, seeds, or other particles or substances to be screened or sieved from assuming an oblique or perpendicular position while passing over the screens or sieves, and thereby compelling said longer or broader grains, seeds, or other particles to pass over the screens or sieves flatwise, while the shorter, smaller, and narrower grains, seeds, and other particles are permitted to pass through the screens or sieves when the latter are in motion.

My invention consists substantially in a peculiar construction and arrangement of parts, hereinafter fully shown and described, whereby the result above specified is attained in a more eminent degree, or in a more thorough or perfect manner, than hitherto.

A represents a section of a shoe which contains a movable plate, having a suitable degree of inclination, fitted in grooves in the shoe, and secured in position by rods *a* passing vertically through the sides of the shoe. This plate is perforated in sections, forming screens or sieves, as indicated by *B B' B''*, smooth surfaces *C C' C''* being left between, as shown in both figures.

At the lower corners of the screen or sieve there are two upright pins, *D D*, screwed or

otherwise secured to the frame of the screen or sieve.

Upon the screen or sieve there are placed three covers, *E E' E''*, of quadrilateral form, but having their upper and lower sides oblique, with the exception of the lower side of the cover *E''*, the position or angle of which is unimportant. At the upper edge or angle of the upper surface of each cover there is a step or barrier, *F*, and a rectangular slip of wood, *G*, is attached to each end of the covers at their under sides, to serve as supports to elevate the covers above the screens or sieves, to afford space for the passage of the grain, seed, or other particles between the bottoms of the covers and the screens or sieves, and slips *G'* are secured to the ends of the lower inclined sides of the same. The lowest and widest of these covers, *E''*, is placed upon the screen or sieve plate, and kept in position by the pins *D D*.

The slips of wood *G'* are of such a width that the covers are prevented from sliding down in contact with each other, and thereby cause spaces or chutes *H* to be between the covers, which spaces or chutes have an inclined position, corresponding, of course, to the inclination of the sides of the covers. (See Fig. 2.)

The width of the spaces between the sides of the covers—that is to say, the width of the chute *H*—may be about three-sixteenths ($\frac{3}{16}$) of an inch, (more or less,) according to circumstances. These chutes extend the whole width of the screens or sieves, and convey the grain, seed, or other particles to be operated upon obliquely down to the imperforated surfaces *C C' C''* between the perforated portions or screens or sieves *B B' B''*. (See Fig. 2.)

In the upper part of the shoe *A*, above the uppermost cover, *E*, there is secured a strip, *I*, the lower side of which is inclined, corresponding to the inclination of the upper side of cover *E*, and forming the upper side of the upper chute, *H*.

In the upper part of the shoe, near the rods *a*, which secure the screen-plate in position, there is fitted a movable or detachable strip, *J*, over which the grain, seed, or other substance to be operated upon is delivered just above the first chute, *H*.

Under the screen or sieve plate there is an inclined board or chute, K, (shown in Fig. 2,) and to the under side of each cover E E' E'' there is attached, by a clip-plate, A', (see Fig. 2,) a flap or apron, L, of flexible, textile, or other fabric, such as india-rubber, rubber-cloth, oil-cloth, painted cloth, or other suitable material which will form a pliable surface and adapt itself to the grain, seed, or other particles or substances operated upon, and prevent the longer or broader grains, seeds, or other articles or substances from assuming an oblique or perpendicular position while passing over the screens or sieves, thus compelling said longer or broader grains, seeds, &c., to pass over the screens or sieves flatwise, while the shorter, narrower, and smaller grains, seeds, or other particles are permitted to pass through the screens or sieves when the latter are in motion.

The clip-plates A' are attached to the upper inclined side of each cover, the lower ends being bent under the covers and over the edges of the flaps or aprons, and secured by screws, and the upper edges are bent over the upper edges of the covers. (See Fig. 2.) By the use of these flaps or aprons the separator is much more perfect than without, as by their weight or flexibility they adapt themselves to different sizes of grains, seeds, &c., holding them flatwise, and retarding their advance until the separation is more perfectly made, thereby permitting the use of much narrower screens or sieves than would otherwise be necessary with much greater pitch per foot, and accomplishing more and better work in a given time than can be done without them.

The covers E E' E'', when constructed of wood, are liable to warp or twist, and also to expand and contract. In order to avoid the warping and twisting, and to cause the covers to expand and contract as equally as possible at all points, I construct them of a plurality of pieces b, the grain of which is parallel, said pieces being glued or otherwise secured together. The slips of wood G G' are sawed or cut transversely at short intervals, to allow for the expansion and contraction of the covers. The covers are also made hollow, as shown at a*, and, if necessary or desired, supports may be placed within the spaces to prevent the parts from springing.

The quantity of grain, seed, or other particles or substances fed or delivered to the machine passes over the strip J above the upper chute H, and should not be less than will fully supply the three chutes, and the first chute H will receive its complement—one-third the whole amount—which will be conducted down upon the first smooth surface, C, above the screen or sieve B, where all the broader grains, seeds, or other particles or substances are compelled to assume a horizontal position in relation to the screen or sieve B before they arrive at it, compelling such shaped or sized grains, seeds, &c., to pass flatwise over the screen or sieve, so that they cannot pass

through B, while nearly the whole of the smaller grains, seeds, &c., are permitted to pass through B before reaching the second smooth or unperforated surface, C.

The portion of grain, seed, or other particles or substances which does not pass into the first chute H will pass over the first barrier F and advance to the second chute H, which portion will be arrested by the second barrier F and precipitated down the second chute H.

The third chute H receives its quantity in the same manner, the operation being precisely the same.

In case the machine is over-fed the surplus grain, seed, or other substance will fall from the upper surface of the last cover, E, thereby giving notice of the fact, so that the operator can reduce the feed.

All the grains, seeds, &c., which pass through the screens or sieves B B' B'' fall upon chute K, which discharges them upon other screens not shown, and which are not necessarily connected with this invention.

Having thus described my invention, I claim as new and desire to secure by Letters Patent—

1. The construction of covers E E' E'', of suitable thickness, covering the screens or sieves B B' B'', with chutes H between, corresponding in number with the smooth or imperforated surfaces C, and opening obliquely or sloping downward nearly or quite their entire length, said chutes being so located that when grains, seeds, or other substances shall pass downward through them they will fall or be precipitated directly upon the smooth or imperforated surfaces C.

2. Constructing and locating the covers E E' E'' in separate sections, with barriers F at their upper angles, and rectangular slips G G' attached to the ends of said covers to elevate them the requisite height above the screens or sieves B B' B'', and to keep them the proper distance apart to allow the passage of grains, seeds, or other substances in such manner that the oblique or sloping chutes H, through which the grain finds its way upon the smooth or imperforated surfaces C above each screen or sieve, will retain their proper proportions and positions relative to the surfaces C and above each screen or sieve.

3. The flaps or aprons L, composed of flexible, textile, or other fabric—such as rubber, rubber-cloth, oil-cloth, painted cloth, or any preparation or fabric—so attached to the covers E E' E'', or to separate pieces to occupy their places, as to adapt themselves to the inequalities of the screens or sieves B B' B'', and to grains, seeds, or other substances, which may be passed between said flaps or aprons and the screens or sieves in such a manner as to prevent the longer or broader grains, seeds, or other substances from assuming an oblique or perpendicular position while passing over the screens or sieves, thus compelling said longer or broader grains, seeds, or other substances to pass over the screens or sieves flatwise,

while the shorter, narrower, and smaller grains, seeds, or other substances are permitted to pass through them when the screens or sieves are in motion.

4. The building or constructing of covers E E' E'', substantially as herein shown and described, so that they will expand or contract as equally in all parts as possible, and not be liable to warp or twist, thereby prevent-

ing the irregularities in their form which would otherwise occur.

5. Securing the flaps or aprons I to the covers E E' E'' by means of the clip-plates A', as shown and described.

JOHN S. BODGE.
